UNITED STATES PATENT OFFICE

GEORGE ST. PETER, OF BANGOR, MAINE

MANDREL DE-CORER

Application filed May 4, 1931. Serial No. 535,001.

The invention relates to a machine for removing remnants or cores of newsprint or other paper from mandrels upon which rolls of such paper are handled by printing presses or other machines. The paper at the centers of the rolls, is not useable in the machines and must be removed before the mandrels can again be used, and at present, slow, laborious and dangerous hand-operations are employed to cut the cores of paper from the mandrels. My invention however, aims to provide a rapid and efficient machine for removing the cores, without danger to the operator.

With the above object in view, the invention resides in the novel subject matter hereinafter described and claimed, description being accomplished by reference to the accompanying drawings.

Fig. 1 is a perspective view of a machine constructed in accordance with the invention.

Fig. 2 is a fragmentary side elevation partly broken away and in section.

Fig. 3 is a horizontal sectional view on line 3—3 of Fig. 2.

Fig. 4 is a vertical transverse sectional view on line 4—4 of Fig. 2.

Fig. 5 is a fragmentary vertical section on line 5—5 of Fig. 4.

Fig. 6 is a side elevation of the knife-carrying carriage and associated parts, and this view illustrates the manner in which the machine cuts the paper core when the carriage is moved in one direction.

Fig. 7 is an enlarged fragmentary elevation partly in section, showing the manner in which the remaining layers of the paper core are cut when the carriage is moved in the opposite direction.

Fig. 8 is a detail sectional view on line 8—8 of Fig. 7.

Figs. 9 and 10 are horizontal sectional views on lines 9—9 and 10—10 of Fig. 7.

A preferred construction has been illustrated and will be specifically described, with the understanding however that within the scope of the invention as claimed, variations may be made.

The frame structure F of the machine embodies two end frames E which are substantial duplicates. Each of these end members

embodies a vertical standard 12 having two laterally diverging supporting legs 13, the legs at one end of the machine being rigidly connected by a transverse bar 14 carrying a support 15 for an electric motor 16 which is used for propelling the knife-carrying carriage 17 in either direction. This carriage is slideable along a horizontal guideway preferably consisting of parallel rods 18 extending between the upper ends of the standards 12 and rigidly secured to the latter. A horizontal feed screw 19 is provided for the carriage 17, said screw having a threaded engagement with said carriage and having its ends rotatably mounted upon the standards 12. At one of its ends, the feed screw 19 is provided with a reverse gear 20 controlled by a lever 21 or in some other preferred manner, for driving the screw 19 in either direction. A vertical shaft 22 is provided to drive the reverse gear 20, said shaft 22 being driven by the motor 16, through the instrumentality of appropriate gearing 23. 24 merely denotes a bearing bracket for the shaft 22, said bracket being secured to one of the standards 12.

The carriage 17 embodies a vertical slide 25 which may be raised and lowered as required, by means of a hand screw 26, the lower end of said slide being provided with one knife 27 which cuts through the greater part of the mandrel-carried paper core 28, when the carriage 17 moves in one direction, said carriage also having another knife 29 which cuts through the remaining layers of the core upon the return movement of the carriage, leaving the mandrel 30 free of paper. The action of the knives 27 and 29 is illustrated more particularly in Figs. 1, 6 and 7 and will be hereinafter more definitely explained.

In the present showing, the lower end of the slide 25 is provided with a kerf 31 in which the upper portions of both knives 27 and 29 are received, but separate recesses could of course be provided for said knives. The knife 27 is of substantially L-shape and is provided with a cutting edge 32 inclined throughout its length away from the knife 29. The vertical portion of this blade 27 is formed with a slot 33 which receives a key 34

extending across the kerf 31, said slot also receiving a fastener 35 extending across said kerf. When this fastener is tightened, the kerf 31 is transversely narrowed and hence the knife 27 is tightly clamped in place, and the key 34 merely prevents said knife from rocking about the fastener 35.

The blade 29 is vertically elongated and is provided with a vertical cutting edge 36 facing away from the knife 27. This knife 29 is provided with a blunt lower end 37 and with an acute angular nose 38 at the juncture of the edges 36 and 37. The upper end of the knife 29 is formed with a vertical slot 39 through which a pivot 40 passes, said pivot being carried by the slide 25. Knife 29 projects some distance above the pivot 40 and is received in the lower end of a coiled compression spring 41 which is seated in a notch 42 in the slide 25, the upper end of said notch being provided with a stud 43 or equivalent means for holding the upper end of the spring in place. The knife 29 may swing away from the cutter 27, without limit during the operation of the machine, but its swinging movement toward said knife 27 is limited by a stop pin 44 which is carried by the slide 25 and extends across the kerf 31.

When the carriage 17 is traveling in the direction indicated by the arrows A of Figs. 1 and 6, the knife 27 cuts through the greater part of the thickness of the paper core 28, the knife 29 then trailing idly in an outwardly swung position, as clearly shown in Figs. 1 and 6. When the carriage 17 is reversed however, the knife 29 immediately swings inwardly to the extent allowed by the pin 44, with the result that said knife 29 then occupies an operative position (Fig. 7) so that it will cut the remaining layers of paper from the mandrel during the return movement of the carriage. During its operation, the knife 29 slides at its lower end 37, along the mandrel 30 and if any irregularities in this mandrel necessitate that the knife shall move vertically, such movement is allowed by the spring 41, said spring always serving to hold the knife tightly down against the mandrel. By employing the two knives 27 and 29 operating in or substantially in the manner shown and described, the paper may be much more cleanly cut from the mandrel than when attempting to use only one knife to completely cut through the core, for if a knife such as 27 for instance, were used, in order to adjust said knife so that its heel would cut entirely through the core, there would be danger of said heel dragging upon said core and hence seriously dulling the knife so that said heel would tear the paper instead of cutting it and would soon become so obstructed as to be utterly inefficient. There is no such danger however, with the knife 29, for only its blunt edge 37 engages the mandrel 30.

To support the mandrel 30, I provide two centering plugs for reception in the ends of said mandrel, one of these plugs being shown at 45 in Fig. 1 while the other is illustrated at 46 in Figs. 2 and 3. One of these plugs is provided with a suitable lug or the like 47 receivable in a mandrel notch, to hold the mandrel against rotation. Both plugs 45 and 46 are provided with carrying shanks such as 48 (Figs. 1 and 3). The shank 48 of the plug 46 is secured to a slide 49 which may be adjusted to various positions along two horizontal guide rods 50 which extend between the end frames E, the ends of said rods being suitably secured to horizontal angle iron bars 51 which cross the standards 12 and are adjustably connected with the latter. The shank of the plug 45 passes through a vertical slot 52 in the standard 12 remote from the carriage 49 and is secured to the adjacent bar 51. By vertically adjusting the bars 51, the mandrel supporting means may be so positioned that the surface of the mandrel will be absolutely parallel with the carriage guides 18, so that the knives 27 and 29 may operate in proper relation with said mandrel. By moving the slide 49 away from the plug 45, a mandrel whose core has been cut, may be easily removed from the machine, and to insert another mandrel, one end of the latter is engaged with the plug 45 and the slide 49 is then slid along the rods 50 until its plug 46 is properly engaged with the other end of said mandrel. If desired, suitable locking means may be employed for locking the slide 49 in any position to which it has been adjusted.

For securing the bars 51 to the standards 12 and allowing vertical adjustment of said bars, I have shown bolts 53 passing through openings in said bars and through slots 54 in said standards. Jack screws 55 are preferably mounted under these bars 51 to allow easy and accurate vertical adjustment of them when the bolts 53 are loosened, and when said bolts are tightened, the entire mandrel-supporting means will be rigidly held.

In operating the machine, the screw 26 is operated to raise the slide 25 so that the blades 27 and 29 will be entirely out of the way when placing the core-carrying mandrel in the machine. One end of the mandrel is engaged with the plug 45, the slide 49 is then slid inwardly until its plug 46 will properly engage the other end of the mandrel, and said slide is then locked if locking means be provided for it. The screw 27 is now operated to lower the slide 25 so that the knife 27 will cut almost entirely through the core 28 during its travel in the direction A, and the screw 19 is then driven in the proper direction to effect such carriage travel. As the knife 27 operates to cut most of the way through the core 28 (Figs. 1 and 6), the knife

29 merely trails idly in the bottom of the cut, as shown in these views. When the carriage 17 is reversed however, the knife 29 moves to the operative position shown in Fig. 5 7 and cuts through the remaining layers of the core. Hence, movement of the carriage first in one direction and then in the other, effects complete cutting of the paper core from the mandrel and leaves the carriage at 10 the proper end of the machine for starting another core-removing operation.

The general structure shown and described has proven to be desirable from numerous standpoints and is therefore preferably followed. However, within the scope of the invention as claimed, variations may be made, 15 as above stated.

I claim:—

1. A machine for cutting a tubular core 23 from a mandrel, comprising a frame, a carriage guideway carried by said frame, two supports for the ends of a mandrel, said supports being carried by said frame and mounted for relative shifting according to the 25 length of the mandrel, said supports being positioned to support said mandrel in parallel relation with said guideway, a carriage movable along said guideway, a cutter mounted on said carriage for cutting the core, 30 and means for moving said carriage along said guideway.

2. A machine for cutting a tubular core from a mandrel, comprising two rigid end members, two parallel rods extending between said end members and secured thereto, a mandrel-engaging supporting member mounted between said rods at one end of the latter and adapted to engage one end of a core-carrying mandrel, a slide adjustable along the other ends of said rods, a second mandrel-engaging supporting member fixedly carried by said slide and adapted to engage the other end of the mandrel, and means for cutting the core from the mandrel while held by said supporting members.

3. A machine for cutting a tubular core from a mandrel, comprising two rigid end members, carriage guiding means extending between said end members, a carriage movable along said guiding means and having a knife for cutting the core, two supporting members for engagement with the ends of the core-carrying mandrel to hold the latter in position for cutting of the core with said knife, a slide carrying one of said supporting members, two parallel rods along which said slide is movable, said rods being disposed at opposite sides of said supporting members and parallel with said carriage guiding means, two transverse bars to which the ends of said rods are secured, the other of said supporting members being carried by one of said bars, and adjustable means securing said bars to said end members and allowing ad-

justment of said bars and rods toward and from said carriage.

4. A machine for cutting a tubular core from a mandrel, comprising a frame, a carriage guideway carried by said frame, a carriage and means for moving it along said guideway, means for supporting the core-carrying mandrel in parallel relation with said carriage guideway, one knife mounted on said carriage for cutting most of the core thickness as the carriage travels in one direction, a second knife for cutting the remaining thickness of the core as the carriage travels in the other direction, and means movably mounting said second knife on said carriage for allowing said second knife to move idly when the carriage travels in said one direction and for allowing said second knife to move to operative position when said carriage travels in the other direction.

5. A machine for cutting a tubular core from a mandrel, comprising a frame, a carriage guideway carried by said frame, a carriage and means for moving it along said guideway, means for supporting the core-carrying mandrel in parallel relation with said carriage guideway, one knife mounted on said carriage for cutting most of the core thickness as the carriage travels in one direction, a second knife for cutting the remaining thickness of the core as the carriage travels in the other direction, said second knife having a cutting edge at an angle to the line along which the carriage moves, and means pivotally mounting said second knife on said carriage upon an axis transverse to the line of movement of said carriage, whereby said second knife may swing to an idle trailing position when the carriage moves in said one direction and may swing to operative position when the carriage moves in the other direction, said carriage having a stop for limiting the last mentioned swinging movement of said second knife.

6. A structure as specified in claim 4; together with spring means on the carriage for pressing said second knife against the mandrel while in operation, said second knife having a blunt portion independent of its cutting edge adapted to slide along said mandrel.

7. A structure as specified in claim 5, said pivotal mounting means for said second knife embodying means allowing shifting of said second knife transversely of the line of carriage movement, and spring means acting on said second knife for pressing the latter against the mandrel when in operation, said second knife having a blunt edge independent of its cutting edge adapted to slide along the mandrel.

In testimony whereof I affix my signature.
GEORGE ST. PETER.
